METHOD FOR FREEING A CONTAINER OF
ASPHALTIC AND OILY MATERIALSArthur B. Butterworth, Brooklyn, N. Y., assignor
to Butterworth System, Inc.

Application June 10, 1933, Serial No. 675,235

8 Claims. (Cl. 141—1)

This invention relates to the cleaning of containers and more particularly it relates to the washing of a residual deposit including a bottom deposit containing fusible material from the interior of a container through an outlet.

The invention will be fully understood from the following description taken in connection with the accompanying drawing in which latter—

Fig. 1 is a longitudinal sectional view through a tank car of conventional design showing the cleaning mechanism associated therewith;

Fig. 2 is a transverse sectional view taken along the line II—II of Fig. 1 showing a steam nozzle in end elevation; and—

Fig. 3 is a detail view in side elevation of the steam nozzle.

Referring particularly to the drawing, reference numeral 1 designates a tank car of conventional design having a dome 2. The bottom wall 3 of the tank car extends substantially horizontally throughout its extent and is provided at an intermediate portion with a discharge outlet 4. The tank car 1 contains heating coils 6 adjacent its bottom surface, suitably supported from the floor 3 by brackets 7.

Such a tank car may be used in the transportation of oil such as asphaltic base crude oil or its distillates. Such an oil may deposit a heavy coating 8 of dirt, coke sand, asphaltic material or the like together with sludge and scale upon the bottom wall 3 of the tank car as well as the usual deposit or residue of sludge and scale upon the side and end walls of the tank car. In cleaning the tank car a steam nozzle device Z is first placed in the container 1. The steam nozzle device Z comprises a tubular main formed of sections A and B which are disposed on opposite sides of the discharge outlet 4. The tubular main is provided with a plurality of steam nozzles N each formed of a coupling member 10 having a delivery portion 11 with a fan shaped discharge orifice 12. The discharge orifice of each steam nozzle of section A faces toward the right as viewed in Fig. 1 toward the discharge outlet 4. Similarly the orifice of each nozzle of the section B of the steam nozzle device faces toward the left as viewed in Fig. 1 toward the discharge outlet 4. The steam nozzle device is supported in position within the tank car upon the steam heating coils 6 by means of supports 31. The tubular main of the steam nozzle device connects through a T 14 and flexible conduit 15 with a suitable source of steam supply, not shown.

In cleaning the tank car the discharge outlet 4 is opened to permit the free discharge of fluid

therethrough. Steam under pressure is delivered through the nozzles of the steam nozzle device into the deposit upon the bottom of the car. Preferably the steam is ejected under considerable pressure such as fifty pounds per square inch or more. The jets of steam heat a large portion of the bottom deposit to a fluid condition. The application of the jets of steam is continued for a prolonged period of time such as from one to three hours, depending upon the nature and the amount of the deposit of residues. The flow of the bottom deposit toward the discharge outlet is facilitated by the jets of steam which are themselves directed toward the discharge outlet thereby reducing the amount of liquid covering the bottom of the tank car.

After a large portion of the bottom deposit is removed from the car by the jets of steam, the entire interior surface of the car is subjected to a cleaning operation by the following arrangement of parts while continuing the injection of steam through the steam nozzle device. A tank washing machine M is projected into the car through the dome 2 and is held in position to inject water or other cleaning liquid against the entire interior surface of the car. The water or the like is disposed in a tank 17 and is preferably heated through a heating coil 18 connected by means of a pipe 19 to a suitable source of steam or other heating fluid. The water is conducted from the tank 17 by means of a pump 20 having a suction line 21 communicating with the tank 17 and the outlet line 22 through which the liquid from the pump is directed into a pipe 23 of the tank washing machine.

The tank washing machine M is suitably supported at 24 by the cover of the dome 2 of the tank car. The water flows downwardly through the pipe 23 to nozzles 25 through which it is discharged in a solid stream against the sides and bottom of the tank car. It will be noted that the two nozzles 25, one at each side of the pipe 23, are directed in opposite directions. A connecting T 26 is secured rigidly upon a main carrying line 27 within the pipe 23. The line 27 is rotated through a shaft 28 at the upper end thereof and the pipe 23 through which the liquid flows from the line 22 is held stationary. The lower end of the pipe 23 is formed with a stationary gear 29 which is engaged by a gear 30 upon one of the nozzles 25. The rotation of the shaft 28 and the tube 27 leading therefrom rotates the T 26 and the nozzles 25. The engagement between the gear 30 and the stationary gear 29 while the tube 27 is being rotated causes

the nozzles to be rotated in planes parallel with the pipe 23. It is to be understood that the gears 28 and 30 are not of exactly the same size so that the paths of the streams of liquid issuing from the nozzles 25 take a different path on each revolution which they make about the central shaft 27. The shaft 28 is driven in rotation by suitable means such as a manually operated crank, an air motor or the like.

10 In utilizing the tank washing machine the hot water or the like from the tank 17 is delivered from the nozzles 25 under high pressures such as one hundred seventy-five pounds per square inch. The pressure used should be such that the solid jets of liquid issuing from the nozzles 25 will erode or cut the scale and other sediment from the surface to be cleaned. The used liquid is removed through the discharge outlet 4 as fast as it is injected into the tank car and discharged into a settling tank or clarifier not shown, from whence the clarified liquid may be returned to the tank 17 for recirculation thru the system. The removal of the used liquid and dislodged deposits is assisted by the jets of steam 15 which are directed against the bottom of the car and toward the drain, the application of steam being continued throughout the injection of wash liquid into the car. Consequently the high pressure jets impinge directly against the sediment, 20 rust, scale and the like material to be eroded and to be removed with a result that the liquid cleans all of the upper interior surfaces of the car and assists the steam jets in removing the heavy residue still remaining in the bottom.

25 35 Various changes may be made within the scope of the appended claims in which it is desired to claim all novelty inherent in the invention as broadly as the prior art permits.

I claim:

40 1. The method of cleaning a bottom deposit of fusible material from the interior of a container through a bottom outlet, which comprises initially directing jets of steam under substantial pressure against the bottom deposit and toward the outlet whereby a portion of the bottom deposit is melted and propelled toward the outlet and subsequently, while continuing the injection of steam toward said outlet, directing cleaning liquid in streams with force against the bottom 45 wall of the container whereby the remainder of the bottom deposit is blasted from the wall and washed out of the outlet.

50 55 60 65 2. The method of cleaning residual deposit including a bottom deposit containing fusible material from the interior of a container through a bottom outlet, which comprises initially directing jets of steam under substantial pressure against the bottom deposit whereby a portion of the bottom deposit is melted and propelled toward the outlet, and subsequently while continuing the injection of steam toward said outlet, directing cleaning liquid in streams with force against the top, side and bottom walls of the container, whereby the deposits are blasted from the walls and washed out of the outlet.

70 75 3. The method of cleaning residual deposit including a bottom deposit containing fusible material from the interior of a container through a central bottom outlet, which comprises initially directing jets of steam under pressure against the bottom deposit from each end and in the direction of the outlet until a portion of the bottom deposit is melted, blown toward and flowed out of the outlet, subsequently discharging streams of cleaning liquid under pressure

against successively different areas of the top, side and bottom walls of the container, and opposing the centrifugal action induced by the introduction of the cleaning liquid with a centripetal action induced by the injection of steam through the jets directed against the bottom and toward the central outlet from each end whereby the deposits are blasted from the walls and washed out of the outlet.

4. The method of cleaning residual deposit including a bottom deposit containing fusible material from the interior of a container through a bottom outlet, which comprises directing jets of steam under pressure against the bottom deposit for approximately one to three hours and toward the outlet whereby a large portion of the bottom deposit is melted and flowed out of the outlet, and then while continuing the injection of steam toward said outlet directing cleaning liquid in streams with force against the top, side and bottom walls of the container whereby the deposits are blasted from the walls and washed out of the outlet.

5. The method of cleaning residual deposit including a bottom deposit containing fusible material from the interior of a container through a bottom outlet, which comprises directing jets of steam toward said outlet directly into spaced portions of the bottom deposit whereby said portions of the bottom deposit are melted and flowed by progressive stages out of the outlet, and then while continuing the injection of steam toward said outlet directing cleaning liquid in streams with force against the top, side and bottom walls of the container, whereby the deposits are blasted from the walls and washed out of the outlet.

6. The method of cleaning residual deposit including a bottom deposit containing fusible material from the interior of a container through a bottom outlet, which comprises directing jets of steam under pressure against the bottom deposit and toward the outlet whereby a portion of the deposit is melted and flowed out of the outlet, then while continuing the injection of the jets of steam toward said outlet directing cleaning liquid in streams with force against the top, side and bottom walls of the container, and simultaneously removing the used liquid at a rate to maintain the container in a stripped condition with the bottom wall free of a substantial buffer layer of liquid and in condition to be cleaned by the same operation whereby the deposits are blasted from the walls and washed out of the outlet.

7. The method of cleaning residual deposit including a bottom deposit containing fusible material from the interior of a container through a bottom outlet, which comprises directing jets of steam under pressure against the bottom deposit and toward the outlet until a large portion of the bottom deposit is flowed out of the outlet, then while continuing the injection of the jets of steam toward said outlet simultaneously discharging a cleaning liquid in the form of impact high pressure jets under a pressure of not less than forty pounds per square inch into the container while maintaining the bottom of said container substantially free from an interposed buffer layer of the cleansing liquid and while repeatedly changing the point of impact of said liquid under pressure and effecting the repeated circulation of the cleaning liquid withdrawn from the container thru this phase of the operation.

8. The method of washing residual deposit including a bottom deposit containing fusible ma-

terial from the interior of a container through a bottom outlet, which comprises directing jets of steam under pressure against the bottom deposit and toward the outlet until a portion of the bottom deposit is melted and flowed out of the outlet, then while continuing the application of the jets of steam against said bottom and toward said outlet simultaneously directing hot cleaning liquid at high pressure in splashing impact jets under a pressure of not less than 75 pounds per square inch against the side and bottom walls of the container, repeatedly changing

the direction of delivery of the jets of liquid so as to successively impinge against different areas of said container, and withdrawing the used liquid from the container through said outlet at a rate sufficient to maintain the bottom of the container substantially bare of cleaning liquid whereby direct impingement of the cleaning liquid against the bottom deposit is obtained without the interposition of a substantial buffer layer of liquid therebetween.

ARTHUR B. BUTTERWORTH.
